UNITED STATES PATENT OFFICE.

GREGORY L. RUFF, OF PITTSBURG, PENNSYLVANIA.

DESIGN FOR A JEWELRY-CHARM.

SPECIFICATION forming part of Design No. 16,448, dated December 29, 1885.

Application filed October 26, 1885. Serial No. 181,014. Term of patent 14 years.

To all whom it may concern:

Be it known that I, GREGORY L. RUFF, of Pittsburgh, in the county of Allegheny and State of Pennsylvania, have invented a new and original Design for Jewelry-Charms; and I do hereby declare the following to be a full, clear, and exact description thereof, reference being had to the accompanying drawing, forming part of this specification, which represents my design by a perspective view.

My design relates to a jewelry-charm; and it consists in an open book, swords extending diagonally across the book, and a skeleton hand extending over the swords resting on the book and holding them down onto the book.

My design also consists in the combination, with the open book, crossed swords, and skeleton hand, of a sun-like extension at the top of the book.

In the accompanying drawing, *a* is the open book, over which extend the swords *b*, the handles of the swords resting in the upper corners of the book, and the blades extending diagonally over the book toward the lower corners thereof, the swords crossing each other at about the center of the book. Extending over these swords where they cross each other is the skeleton hand *c*, the hand thus holding the swords down upon the book. At the top of the open book *a* is the extension *d*, having a semicircular portion, *e*, in which may be

placed a precious stone, and a series of lines extending radially therefrom, thus imparting to the extension the appearance of the rising sun. The extension has also radial slots *f* 35 therein, and at the top thereof are balls *g*, while the edges of the extension are star-shaped between these balls.

The charm may be used as a pin or as a pendant, and in the latter case is provided 40 with a loop, *h*, to connect it with a suitable link or chain.

What I claim as my design, and desire to secure by Letters Patent, is--

1. The design for a jewelry-charm herein 45 shown and described, consisting of an open book, swords extending diagonally across the book, and a skeleton hand extending over the swords and holding them down onto the book.

2. The design for a jewelry-charm herein 50 shown and described, consisting in an open book, a skeleton hand extending over the swords and holding them down onto the book, swords extending diagonally across the book, and the sun-like extension at the top of the 55 book.

In testimony whereof I, the said GREGORY L. RUFF, have hereunto set my hand.

GREGORY L. RUFF.
